UNITED STATES PATENT OFFICE

JOHN E. RENFER, OF CLEVELAND, OHIO, ASSIGNOR TO THE CLEVELAND ROCK DRILL COMPANY, OF CLEVELAND, OHIO

DRILL-STEEL RETAINER

Application filed March 12, 1928. Serial No. 261,137.

The present invention is directed to improvements in drill steel retainers.

The primary object of the invention is to provide a device of this character so constructed that the same can be connected with one of the side rods of the drill, thereby eliminating the use of additional fastening devices, and materially adding to the simplicity of the structure.

10 Another object of the invention is to provide a device of this kind wherein the shock incident to the drill steel collar striking the retainer will be effectively absorbed, thus prolonging the life of the device.

15 Another object of the invention is to provide a retainer capable of being easily and quickly swung to its open or closed position.

While the drawing illustrates a preferred embodiment of the invention it is to be understood that in adapting the means to meet specific needs and requirements, the design may be varied and such other changes in the minor details of construction may be resorted to within the scope of the invention as 25 claimed, without departing from the spirit thereof.

For a full understanding of the invention and the merits thereof, reference is to be had to the following description and the drawing 30 hereto attached, in which,—

Figure 1 is a side view.

Figure 2 is a front view.

Corresponding and like parts are referred to in the following description and designated in the several views of the drawing by 35 like reference characters.

Referring to the drawing, 1 designates the front head of a percussive rock drill, and 2 and 3 the side rods, the former being somewhat longer than the latter and is provided 40 with an extension 4 upon its lower end, the purpose of which will be later explained.

The holder 5 for the retainer consists of upper and lower substantially circular horizontally disposed flanges 6 and 7, respectively, integrally connected by a bar 8. These flanges are formed respectively, with openings 9 and 10, arranged in direct alinement with each other. The inner face of the bar 50 8 is formed with a longitudinal transversely

curved groove 11 in order to snugly engage the side rod spring 12 in order to compactly assemble the parts. A coil spring 13 is used in connection with the side rod 3, as is customary. The flange 7 has carried thereby an integrally connected hook 14 for pivotal engagement with the retainer 15.

The retainer 15 is formed from a single blank of suitable metal and comprises angularly disposed sections 16 and 17, the section 16 having an opening 18 therein which communicates with the slot 19 of the section 17. The diameter of the opening 18 is such that the collar 20 of the drill steel 21 can pass therethrough in order that the steel can be removed or replaced, while the width of the slot 19 is such as to prevent passage of the collar 20 therethrough. The section 16 of the retainer is further provided with an eye 22 for pivotal engagement with the hook 14 in order that the retainer can be conveniently swung open or closed.

The coil spring 12 used in connection with the side rod 2 and holder 5 has a lug 23 upon its upper terminal which engages a recess 24 formed in the lock washer 25 interposed between the nut 26 and said spring.

It will be noted that the upper flange 6 normally engages the shoulder 27 of the front head 1 and that the side rod 2 passes through the opening 9 with the extension 4 engaged in the opening 10, and since the spring 12 encircles that portion of the side rods between the flanges 6 and 7, the holder will be yieldably maintained upon the side rod due to the presence of the nut 26.

The eye 22 is engaged in the hook 14 and at which time the rim thereof will be held tightly in engagement with the extension 4 due to the resiliency of the spring 12, thereby preventing accidental disengagement of the holder 5. It will be obvious that when the drill steel is rapidly projected forwardly and the collar thereof strikes the section 17, the shock incident thereto will be absorbed owing to the fact that the holder may slide upon the side rods. This action of course contracts the spring 12, but as the spring expands the holder will return to its normal position.

Since the retainer 15 is pivotally connected to the hook 14 through the medium of the eye 22 said retainer can be conveniently swung upwardly to a position to permit the drill 5 steel collar 20 to pass through the opening 18 when changing or replacing steels, and downwardly in order to limit the outward movement of the steel.

Having thus described the invention, I 10 claim:

1. The combination with the front head of a drill having a collared drill steel operatively associated therewith, of a side rod extending from the front head and having an extension, 15 a holder slidably and yieldably connected with the side rod, a hook carried by the holder, and a drill steel retainer pivotally connected to the hook and yieldably engaged with said extension.
- 20 2. The combination with the front head of a drill having a collared drill steel operatively engaged therein, of a side rod extending from the front head and having an extension upon its extended end, a holder slidably and yieldably engaged with the side rod, a hook carried by the holder, said extension extending into the hook, a drill steel retainer pivotally engaged with the hook and by said extension.

In testimony whereof I affix my signature.

JOHN E. RENFER.
